Int. Cl. D14—03

U.S. Cl. D56—4

The single figure is a left side, top and front perspective view of a combined radio-phonograph and tape player or similar article, showing my new design.

The opposite side, not shown, is substantially a mirror image in perspective of the side shown.

The back and bottom, not shown, are essentially plain.
I claim:

The ornamental design for a combined radio-phonograph and tape player or similar article, as shown and described.
